UNITED STATES PATENT OFFICE

104,792

DESIGN FOR A STAIR TREAD MAT

Hunter McKay, Cambridge, Mass., assignor to Boston Woven Hose & Rubber Company, Cambridge, Mass., a corporation of Massachusetts

Application October 30, 1936, Serial No. 65,604

Term of patent 14 years

To all whom it may concern:

Be it known that I, Hunter McKay, a citizen of the United States, residing at 51 Wendell Street, Cambridge, in the county of Middlesex and Commonwealth of Massachusetts, have invented a new, original, and ornamental Design for a Stair Tread Mat, of which the following is a specification, reference being had to the accompanying drawing, forming a part thereof, in which

The figure in the drawing is a perspective view of a stair tread mat embodying my novel design, the design shown in the first section being repeated in the adjacent and succeeding sections.

I claim:

The ornamental design for a stair tread mat substantially as shown and described.

HUNTER MCKAY.
